US00D923311S

(12) United States Design Patent (10) Patent No.: US D923,311 S
Barrera et al. (45) Date of Patent: * Jun. 29, 2021

(54) FOOTWEAR

(71) Applicant: Allbirds, Inc., San Francisco, CA (US)

(72) Inventors: Dennice Quijano Barrera, San Francisco, CA (US); Thomas Jad Finek, San Francisco, CA (US); Jamie McLellan, San Francisco, CA (US); Olivier Henrichot, San Francisco, CA (US); Romesh Patel, San Francisco, CA (US); James Romero, San Francisco, CA (US)

(73) Assignee: Allbirds, Inc., San Francisco, CA (US)

() Term: 15 Years

(21) Appl. No.: 29/699,865

(22) Filed: Jul. 30, 2019

(51) LOC (13) Cl. 02-04

(52) U.S. Cl.

USPC D2/969

(58) Field of Classification Search

USPC ..... D2/896, 900, 902, 904, 906–908, D2/916–924, 925–945, 969, 970–979; 36/1.5, 3 A, 83, 45, 99, 101, 112–116, 36/136

(57) CLAIM

We claim the ornamental design for footwear, as shown and described.

DESCRIPTION

FIG. 1 is a perspective view of footwear, showing our new design;

FIG. 2 is a right side view thereof;

FIG. 3 is a left side view thereof;

FIG. 4 is a front view thereof;

FIG. 5 is a back view thereof;

FIG. 6 is a top view thereof; and,

FIG. 7 is a bottom view thereof.

The broken lines show portions of the footwear that form no part of the claimed design.

1 Claim, 6 Drawing Sheets
